UNITED STATES PATENT OFFICE.

ZALMON G. SHOLES, OF NEW YORK, N. Y., ASSIGNOR; BY MESNE ASSIGNMENTS, TO THE LAWRENCE MANUFACTURING COMPANY LIMITED, OF LONDON, ENGLAND.

TYPE-WRITER.

1,112,851.

Specification of Letters Patent.

Patented Oct. 6, 1914.

Application filed November 17, 1911. Serial No. 668,826.

To all whom it may concern:

Be it known that I, ZALMON G. SHOLES, a citizen of the United States, residing at New York city, in the county of New York 5 and State of New York; have invented certain new and useful Improvements in Type-Writers; and I do hereby declare the following to be a full, clear, and exact description of the invention; such as will enable others 10 skilled in the art to which it appertains to make and use the same.

The present invention has relation to certain improvements in the case shift of a typewriter and the advantages of the improvement will appear in connection with the following description of the invention.

Certain preferred forms of the invention are illustrated in the accompanying drawings, wherein—

20 Figure 1 is a partial plan view of the type bars and their carrying means, Fig. 2 is a perspective view of a portion of the type carrying segment, Fig. 3 is a vertical view of a portion of the same partly in section, 25 and Figs. 4 and 5 respectively are a plan and section of the preferred segment shifting lever.

The type bars are arranged in the usual nest shown at 20 so as to fall back upon the 30 usual rest 21 which is of a nature to deaden the sound of the return. The type bars are operated by links attached to them pivotally as shown at 22, and are pivotally supported upon a segmental support 23 adapted to be raised and lowered in the improved manner about to be disclosed. At each end of the segment 23 are arranged ears 24 and 25 which are centrally perforated to fit over suitable upright columns or 35 supports 26 and these columns are fitted with movable stops in the form of clamping sleeves 27 and 28 which can be tightened in any position at will, by means of the screws 29 and 30. This construction permits the 40 upper and lower limits of movement of the segment 23 to be accurately and independently adjusted in a simple and easy manner. As shown in Fig. 2 the weight of the segment is carried by the ears 24 resting on the 45 clamp stops 27, and similarly the clamp stops 28 limit the upward movement of the segment. I prefer to use a simple means for partly counter-balancing the weight of the segment 23, which means is shown 50 plainly in Fig. 1 of the drawings. In the

form shown a rod 31 is pivoted at its ends at 32 and 33 in a position parallel to the length of the segment 23. A spiral spring 34 surrounds this rod and one end thereof engages with the frame work of the machine 60 as shown at 35, while the other end is fixed to a block 36 which is adjustably fixed on the rod 31 by means of the screw 37. By this means, the tension of the spring 34 can be easily adjusted. The rod 31 is furnished 65 with two levers 38 and 39 which engage the opposite ends of the segment 23, and the effort of the spring 34 is such that these arms tend to lift the segment and aid its upward movement.

The shifting of the segment upward is preferably accomplished by the means shown in Figs. 2 to 5 inclusive. The lever 40 is pivotally mounted by means of a fixed rod 41 and a link 42 is pivoted to the end of the lever 40 and its opposite end is pivoted as shown at 43 in Fig. 3, to the segment 23. Beneath the lever 40 and resting against the under surface thereof is a roller 44 which is rotatably carried at the end of a lever 45 which is pivotally attached at 46 to the shifting key lever 47 carrying the usual knob or key 48 for receiving pressure of the finger. The shifting lever 47 is extended beyond the pivotal mounting 46 and is provided with a strap 49 which loosely surrounds the lever 45 carrying the roller 44. Screws 50 and 51 are placed in the top and bottom of the strap 49 and serve to abut against the upper and lower surfaces respectively of the lever 45 when the segment is to be shifted. In operating this shifting segment to raise the same, the key 48 is depressed until the screw 51 strikes the lever 45 and pushes the roller 44 up under the lever 40. This pressure tilts the lever 40 and acts through the link 42 to raise the segment. The object of the loose connection just described for operating the lever 45 and roller 44 is to permit free adjustment of the position up and down of the segment 23 without interfering with the normal position of the key lever 47, and finger key 48.

Just in front of the printing point on the platen, a bracket 52 is fixed to the top of the segment 23 which bracket is cut out at 53 to provide the guide for the type bars in a well known manner. One side of the bracket 52 is extended as shown at 54 and carries a light spring wire 55 arranged sub- 110

stantially as shown so that its end lies across the top of the guide opening 53. This spring 55 is pushed forward each time that a type impression is made and it serves to 5 certainly throw back each type bar after such impression and prevent any danger of sticking.

Various modifications of structure may be introduced into my improved device without 10 departing from the spirit of my invention and I do not limit myself to the details shown and described.

What I claim is—

1. In a typewriter, a type-bar segment 15 mounted for movement up and down, a pivoted lifting lever connected thereto, a roller for lifting said lever, a pivoted finger lever adapted to raise said roller, and means for adjusting at will the normal vertical rela-

tion between said finger lever and said roller, 20 substantially as described.

2. In a typewriter, a type-bar segment mounted for movement up and down, a pivoted lifting lever connected thereto, a roller for lifting said lever, a two part pivoted 25 finger lever one part of which is adapted to directly lift said roller, a finger button on the other part of said finger lever, and adjustable means for transmitting movement from one part of said finger lever to the 30 other, substantially as described.

In testimony whereof, I affix my signature, in presence of two witnesses.

ZALMON G. SHOLES.
